THERMOSTATIC RELAY

Olav Amandus Johansen, Langhus, Norway, assignor to El-Ka Elektrisk Apparatfabrikk, Langhus, Norway

Application May 16, 1952, Serial No. 288,350

Claims priority, application Norway May 23, 1951

5 Claims. (Cl. 200—122)

1

This invention principally relates to an electric thermostatic relay. One of the objects of the invention is to provide special means in connection with a relay of said type, whereby the action of the relay, that is its time of function, may be varied as desired for adapting the relay for different purposes.

According to the invention this part of the problem is solved by providing the relay with an electric heating element and a bimetallic rod or plate, which is heated by said heating element. According to the invention these two elements, the heating element and the bimetallic rod are so related to each other that the heat action of the heating element upon the rod may be varied.

In a preferred embodiment of the invention, the heating element is stationary attached in relation to the frame of the relay, whereas the bimetallic rod is axially displaceable in relation to the heating element, so that the effective length of the rod may be varied according to desire.

A further object of the invention consists in the introducing, in a relay of the above mentioned type, of an actuating organ in the form of a two-armed lever, which is rockably attached to the frame and one arm of which is actuated by the bimetallic rod, when the latter operates, whereas the other arm serves to effect the function or give the impulse for which the relay is destined, e. g. for opening or closing of electrical contacts. According to the invention that arm of the actuating organ which is influenced by the bimetallic rod is provided with a step-arrangement, so that the bimetallic rod may contact the actuating organ at different places, that is against the different steps, according to the axial adjustment of the bimetallic rod in relation to the heating element.

In a preferred embodiment of the invention said step-arrangement takes the form of a slot or cut-out in said arm of the actuating organ, so that the bimetallic rod may act upon the arm in both directions, a backlash for the bimetallic rod occurring from the same acting upon the arm in one direction thereof until it acts upon said arm in the other direction.

Further the invention relates to a special arrangement of the electrical contact organs of an electric thermostatic relay of the above mentioned type. In this connection the object of the invention is to provide contact organs which will have a snap action in the opening as well as in the closing of the contacts, so that rapid connection and rapid disconnection are obtained, and no sparks will occur.

2

According to the invention this is made possible thereby that one of the two contacts intended for cooperation is carried by a spring the free end of which is provided with a roller adapted to abut against another roller carried by another spring attached to the frame of the relay in such manner that the two springs extend in directions towards each other. By suitable choice of the lengths of these two springs is obtained that the rollers are at any time resiliently contacting each other, but that their axes may be displaced in relation to each other, so that in one case the axis of one roller is at a higher level than that of the other, and in another case such relation is inverted.

15 In the passing from one position to the other a snap action thereby is obtained, which gives the desired rapid closing or breaking of the contacts. In combination with the above described arrangement of an actuating organ said contact 20 devices are so arranged that when the contact is to be opened the free end of the actuating organ presses against said spring arm which carries one of the contacts and when this pressure attains a sufficient value the two rollers are 25 displaced in relation to each other, and the contact is opened with snap action.

According to the invention the arrangement may be of special value in connection with electric relays intended for breaking of a current flow after a predetermined period of time. This period of time begins when the thermostatic relay is started, by manual or other operation, by exertion of a pressure against the top side of the spring carrying the contact.

30 Further the invention consists of the combination of a relay of the above cited type with a thermostatically controlled electric apparatus for heat treatment of a work for a certain period, e. g. a slice of bread to be toasted.

Electric toasting apparatus are well known in 40 which a slice of bread is placed between two heating elements and release devices are provided which release the slice and raise the same when the slice has been under the action of the heating elements for a sufficient period of time.

45 In connection with such an apparatus the invention is made use of by providing the toasting apparatus with a spring actuated frame which normally keeps the slice of bread in raised position. When the slice is to be toasted it is moved downwards between the two heating elements, the frame being moved downwards and kept in position for a certain interval of time by means of a holding magnet. According to the invention the frame when being moved downwards 50 establishes contact between said spring supported

contact members of the thermostatic relay, whereby current flows through the heating element of the thermostat and through the magnet which maintains the frame in lowered position. The bimetallic rod then is heated and bent downwards and acts upon the actuating member, whereby the spring actuated contacts are separated after a predetermined period of time.

According to the invention there is provided a secondary contact which is maintained open by the actuating organ as long as the bimetallic rod is cold, but which is closed when the bimetallic rod curves due to heating thereof. Just before opening of the contact providing current supply to the heating element of the thermostat said contacts are closed, whereby a circuit to the electromagnet is established through a suitable resistance, so that the slice of bread, or the like, is continually heat treated. Only when the bimetallic rod of the thermostat straightens and presses in opposite direction against the actuating member the contact providing current to the electromagnet is opened, and the frame carrying the slice of bread is raised to move said slice away from the heating element used for toasting the bread. The device now is ready for performing the same operation once more.

In order that the invention may be easily understood it will below be described in connection with the drawings which disclose an embodiment of the thermostatic relay according to the invention with diagrammatical indications of arrangements for the electric apparatus thermostatically controlled by means of this thermostat. In the following description also other technical features covered by the invention will be described.

Fig. 1 is a perspective view of a thermostatic device according to the invention with a wiring diagram for an electric apparatus controlled by the thermostat.

Figures 2-9 illustrate, diagrammatically, different positions of parts of the thermostat, to explain the operation of the thermostat. Thus Fig. 2 shows the thermostat when carrying no current.

Fig. 3, right part, shows the thermostat at the moment when current is supplied to the heating element.

Fig. 4 illustrates the bimetallic rod in its first phase of downward bending.

Fig. 5, right part, illustrates the bimetallic rod in its last phase of downward bending.

Fig. 7 corresponds to Fig. 4, but shows the bimetallic rod displaced further forwards in relation to the heating element.

Fig. 9 is a corresponding view but with the bimetallic rod moved fully backwards. Fig. 2, right part, shows the contact device of the thermostat in free position. Fig. 3 shows the contact device after the thermostat having been started. Fig. 4 shows the contact device after the bimetallic rod having started to act upon the actuating member, and Fig. 5 shows the contact device when the actuating member interrupts the circuit to the heating element of the thermostat. Fig. 6 shows the bimetallic rod and the actuating member, after the last phase of a period of time, the position being the same as in Fig. 2.

On Fig. 1 of the drawings numeral 1 designates the frame of the thermostat. 2 is the electric holding magnet for the work to be treated. 3 is the main heating element used for treatment of the work. 4 designates a resistance.

On the thermostat frame 1 is provided a heating element 5 having electrical voltage supplied

thereto through wire 16, holding magnet 2, wire 17, terminal 18, bar 19 and wire 20, and back through wire 21, contact springs 22 and 25, double-contact spring 26, bar 27, terminal 28 and wire 29-30. Below the heating element 5 is provided a bimetallic rod 6 attached to an arm 7 which by means of a control member 8 may axially displace the bimetallic rod 6 in relation to the stationary mounted heating element 5. The bimetallic rod 6 has a nose 39 adapted to be received within a stepped or inclined opening 12 in one arm 9 of a two-arm actuating member 9-10, which is pivoted on the frame at 11, the free end 10 of its other arm serving to act upon the contacts for controlling the current passage when the relay is operating.

The function and operation of the relay is best understood by reference to Figs. 2-9. The right parts of Figs. 2-6 exactly illustrate the operation of the bimetallic rod in connection with the actuating organ.

Fig. 2 illustrates the device in inoperative position thereof, that is prior to voltage having been impressed upon the heating element 5, this Figure showing the bimetallic rod 6 in its position of rest. Fig. 3 shows the device at the moment when the element 32 has been pressed down and voltage has been supplied to the heating element 5. Fig. 4 shows the device when the bimetallic rod 6 has started to bend downwards and has abutted against the middle step 14 of the arm 9. Fig. 5 shows the situation when the bimetallic rod 6 has become entirely bent and the actuating arm 9-10 has been swung as far as possible for releasing element 5. Fig. 7 shows the same situation as Fig. 4 but in Fig. 7 the arm 7 has been moved forwards by means of the control member 8, so that the bimetallic rod 6 abuts against the lowermost step 13 of the actuating arm 9. Fig. 3 shows the same situation as Fig. 4 but in Fig. 8 the arm 7 has been moved forwards by means of the control member 8, so that the bimetallic rod 6 abuts against the middle step 14 of the actuating arm 9. Fig. 9 shows a situation similar to Figs. 4 and 7, where the bimetallic rod 6 has been moved backwards so that it abuts against the top step 15 of the actuating arm 9.

As will be understood the described simple arrangement makes it possible to obtain, by axial displacement of the bimetallic rod, different lengths of periods of time in the swinging movement of the actuating arm 9-10, whereby the period elapsing from start to end of the operation of the device may be shortened or lengthened.

The left parts of Figs. 2-6 show the same left end as that of Fig. 1 and illustrate a special contact arrangement suitable for use for example in connection with a bread slice toasting apparatus. Of special importance is here that the contact arrangement is such that a snap action is obtained and formation of sparks between the contact is prevented. A leaf spring 25 carries a contact 31 cooperating with a contact 32 for providing flow of current from terminal 28 through the bar 27 and the double-contact spring 26 to the heating element 5 of the thermostat. At its outer end the spring 25 carries a roller engaging a roller 23 carried by a leaf spring 22 which is attached to a supporting spring 37 which is secured to the frame of the relay and which extends in a direction opposite to that of the leaf spring 25. The lengths of the leaf springs 25 and 22 are so chosen that the rollers contact each other. Closing of contacts 31-32 take place by pressing the

organ 38 downwards against the spring 25 whereby the contact members 31 and 32 make contact and the rollers 23 and 24 at the same time move from the position shown on Fig. 2 to that shown on Fig. 3. Thereby a circuit is closed through the heating element 5, wire 21, spring 22, rollers 23, 24, spring 25, contacts 31—32, spring 26, bar 27, terminal 28, wires 29—30 and back to the source of voltage.

Another spring 36, which is coupled in parallel to the bar 19 through the holding magnet 2 and the resistance 4, carries a contact 33 which operates with a contact 34 connected to the double-contact spring 26, the bar 27 and the terminal 28. Said contacts are open during the first part of the operation period but are closed just before contacts 31—32 are opened, the bimetallic rod being heated and bending down to rock the actuating organ 9—10, as will be understood from and inspection of Fig. 4. Thereafter the actuating organ 9—10 continues to rock whereby the spring 25 with roller 24 snaps past the roller 23 and contacts 31—32 are opened, so that the supply of current to the heating element 5 is interrupted.

Just before the opening of contacts 31—32 a circuit, previously described, is closed over contacts 33—34, the double-contact spring 26, bar 27, terminal 28 and wires 29 and 30, back to the source of current, see Fig. 5. As the bimetallic rod now is cooled it swings back and presses the actuating organ 9—10 in the opposite direction, whereby contacts 33 and 34 are moved away from each other, and the situation becomes that shown on Figures 2 and 6. The holding magnet 2 now is deenergized and the frame holding the piece of work in relation to the heating element 5 raises the piece of work, so that the heat treatment is discontinued.

I claim:

1. A thermostatic relay having an actuating member comprising a frame, a bimetallic member, a rockable actuating arm the movement of which is controlled by the bimetallic member, a leaf spring one end of which is provided with a roller, a second leaf spring having a roller resiliently abutting against the roller carried by the first-mentioned leaf spring and secured to the frame, the leaf springs being directed towards each other, a contact mounted on the first-mentioned leaf spring and a contact mounted on the frame adapted to contact the contact on the first-mentioned leaf spring, the two rollers when pressing against the first-mentioned leaf spring

will snap past each other with snap action to cause fixed contact engagement between the said contacts or will, with snap action, move said contacts away from each other, and said actuating arm upon heating of the bimetallic member provides said pressure against the first-mentioned leaf spring to open the contacts.

2. A thermostatic relay according to claim 1, in which a second set of contacts are provided so that the bimetallic member in combination with the actuating arm controls one set of contacts that is opened when the bimetallic member is hot and the second set of contacts is opened when the bimetallic member is cold.

3. A thermostatic relay according to claim 1, in which a second set of contacts are provided so that the bimetallic member in combination with the actuating arm controls one set of contacts that is opened when the bimetallic member is hot and the second set of contacts is opened when the bimetallic member is cold, and in which a heating element is provided mounted adjacent the bi-metallic member, one of the contact sets being closed manually and the other set being maintained open until the bimetallic member becomes hot and said first-mentioned contacts being opened by said actuating arm to interrupt the current supply to the heating element, whereafter the bimetallic member is cooled so that the second set of contacts are opened.

4. A thermostatic relay according to claim 1, in which said actuating member consists of a two-armed lever pivotally mounted on the frame of the thermostat, one of the lever arms being inclined to form abutments for the bimetallic member at the different positions of the latter.

5. A thermostatic relay according to claim 1, in which a heating element is stationary in the frame of the member and is provided mounted adjacent the bimetallic relay, and in which the bimetallic member is displaceable longitudinally thereof to vary its free length.
